UNITED STATES PATENT OFFICE.

WILLIAM KANTER, OF CLEVELAND, OHIO, ASSIGNOR TO THE KANTERS STAMPING & MANUFACTURING COMPANY, OF CLEVELAND, OHIO, A CORPORATION OF OHIO.

HINGE.

1,384,260.

Specification of Letters Patent. Patented July 12, 1921.

Application filed January 19, 1917. Serial No. 143,210.

To all whom it may concern:

Be it known that I, WILLIAM KANTER, a citizen of the United States, residing at Cleveland, in the county of Cuyahoga and State of Ohio, have invented a certain new and useful Improvement in Hinges, of which the following is a full, clear, and exact description, reference being had to the accompanying drawings.

10 This invention relates to improvements in hinges, and it has for certain of its objects the production of a hinge that is especially suitable for hanging screen doors; that involves an angle plate which is adapted to engage the front and side surfaces of the door or closure and which is designed to accommodate fastening means, such as screws, disposed at right angles to each other; that involves a second plate pivotally connected 15 to the first and which may be offset rearwardly from the front plane of the door or closure substantially the thickness thereof and arranged for attachment directly to the door frame, thus obviating the use of filler 20 blocks or the like made necessary in the use of ordinary hinges in hanging screen doors where the door is wanted to abut against the face of the frame.

A further object of the invention is the 30 economical production of a hinge of the above character practically entirely from sheet metal so designed as to permit of easy access to the connecting means or screws whereby it is attached to the closure and frame. A further object is to construct the 35 hinge so that a part of one plate is arranged to be engaged by the other and thus constitute a stop to limit the movement of said other plate in a direction in which it is 40 adapted to be impelled by a spring which may be incorporated in the hinge. And a further object is to include a sheet metal sleeve for incasing the spring and which is preferably held in place by the spring and parts 45 of one of the plates without the need of other securing means.

In the accompanying drawing which constitutes a part hereof, I have shown a hinge wherein the foregoing objects are attained. 50 Figure 1 is a fragmentary perspective of a screen door attached to a frame by the use of a hinge of my invention; Fig. 2 shows, in perspective, the various elements of the hinge separated; and Fig. 3 is a central

horizontal section through the hinge and 55 the adjacent parts of the door and frame.

Describing the invention by the use of reference characters, 1 represents an angle plate that is adapted to be attached to the front and side surfaces of a screen door or 60 other closure A, by means of the screws or their equivalents 2 and 3, respectively. It will be observed that the screws 2 enter the front of the door at right angles to the screw 3 which enters the side thereof, thus rendering the connection between the angle plate and the door very secure. Wings 4 extend at right angles from each end of the plate 1 and are provided with apertures 5.

A second plate 6 is shown as secured to 70 the frame B by fastening means or screws 7, and this plate is also provided with wings 8 which extend at right angles from its ends and overlap the wings 4 of the former plate, the wings 8 having apertures 9 which are 75 adapted, when the parts are in correct relative position, to align with the apertures 5 of the former plate for the reception of a rivet or pintle 10.

A spring may be included for maintaining 80 the spring plates in normal relative position with the door closed, such a spring being shown at 11. The spring surrounds and is held in place by the pintle 10 with one of its ends engaging the plate 1 adjacent one of 85 its wings 4 and with its opposite end engaged over a hook 12 that is struck up from the wing 8 of the remote end of the plate 6. A stamped metal sleeve 15 surrounds and incases the spring 11, the sleeve being 90 notched at 16 and 17 for the accommodation of the ends of the spring, and the end portions of the spring engaging the vertical walls of the notches 16 and 17 hold the sleeve 15 against unduly turning upon the spring 95 and revealing its open side.

The portion of the angle plate 1 which is intended for engagement with the side of the door or closure is of sufficient width to abut the inner edge of the plate 6. Thus a 100 stop is provided for limiting the movement of the plate 1 by the spring 11. Brackets 18, which may be struck up from either the plate 6 or its wings 8, fill the angles 105 between the plate and its wings and strengthen the plate to withstand the weight of the door or closure. It will be observed that all of the fastening means or screws are

easily accessible for the purpose of attaching or detaching the hinge; and while the hinge is of substantial construction and attractive appearance, it is economical of manufacture, practically the entire structure being formed of sheet metal stampings which, when assembled, are held together and in correct relation to each other because of their peculiar design and arrangement by 10 the sole means of the pintle 10.

Having thus described my invention what I claim is:—

1. A hinge comprising an angle plate adapted to engage the front and side surfaces of a closure and designed to accommodate fastening means disposed at right angles to each other, and a second plate pivotally connected to the first and forward of said front surface, said second plate being 15 offset rearwardly from the plane of the front surface of the closure, the second plate having a part which constitutes a stop to limit the movement of the first plate when the closure is swung to closing position.
2. A hinge comprising an angle plate adapted to engage the front and side surfaces of a closure and designed to accommodate fastening means, certain of which enter the side and others the front of the 20 closure, a second plate offset rearwardly from the plane of the front surface of the closure, said plates having overlapping portions disposed beyond the front surface of the closure, and means pivotally connecting 25 said plates, the second plate being designed to permit easy access to the fastening means which enters the side of the closure when the closure is in closing position.
3. A hinge comprising an angle plate 30 adapted to engage the front and side surfaces of a closure, wings extending from the ends of the plate in substantially parallel relation to each other, a second plate offset rearwardly from the plane of the 35 front surface of the closure and having wings which extend forwardly and overlap 40

the wings of the former plate, a pintle pivotally connecting the overlapping wings of the plates, a spring surrounding the pintle and having one end in engagement with the 50 front portion of the angle plate, the other plate having a projection on one of its end wings for holding the opposite end of the spring, a sleeve disposed between the opposed end wings of the plates and inclosing 55 the spring, the second plate having a portion constituting a stop to be engaged by and limit the movement of the first plate in the direction in which it is impelled by 60 said spring.

4. A hinge comprising a sheet metal plate adapted to be attached to the front and side surfaces of a closure, wings extending from the ends of the front surface of the plate in substantially parallel relation to each other, a second sheet metal plate offset rearwardly from the parallel to the plane of the front surface of the closure and having wings which extend forwardly and overlap the wings of the former plate, brackets between 70 the body portion of the second plate and its wings and disposed at right angles to the wings, and means pivotally connecting the overlapping wings of the plates.

5. A hinge comprising two sheet metal 75 plates each having end wings which overlap the end wings of the other, a pintle pivotally connecting the end wings of the two plates, a spring surrounding the pintle and having an end engaging each plate, and a 80 sheet metal sleeve incasing the spring and having its inner side open and notches in its ends for the occupancy of the end portions of the spring, wherefore the sleeve is held against turning to reveal its open 85 side.

In testimony whereof, I hereunto affix my signature in the presence of two witnesses.

WILLIAM KANTER.
